Alfred W. B. Frederick ^{Inventor}

UNITED STATES PATENT OFFICE

ALFRED W. B. FREDERICK, OF MANILA, PHILIPPINE ISLANDS

BUTTON FASTENER

Application filed July 22, 1929. Serial No. 380,160.

This invention relates to button fastenings and to all other fastenings of a similar nature.

This invention embraces, generally speaking, a button having an eye for securing it to the article to which it is to be applied, a two coil round spring wire, a half-eye in either coil of the round spring wire and of sufficient diameter to accommodate the diameter of the wire forming the eye of the button to be used, the free ends of the wire spring being raised from the points of contact with the center strand of the coil for a distance of three mm. from their points at an angle of twenty-five degrees (25°), the half-eye in either wire of the two coil round spring fastener being directly across the space within the coils from the free ends of the wire, the points of the ends of the wire coils being rounded to a blunt state, and the coil ring fastener being circular in form.

A better knowledge of the features of this invention will appear in the description of the one sheet of drawing accompanying this specification, in which I have shown a button with my fastener attached and also detached, and in which:

Figure 1 is the edge-elevation view of a button with my button-fastener engaged and all the parts of same assembled in their final position.

Fig. 2 is the disengaged button-fastener showing the features to be patented uncovered and in their actual combination position.

In the figures the button 1 has the usual fastening eye 2. When located on the button-fastener 4, the eye of the button lodges in the half-eye 3 of the fastener and is loose to articulate but is held in the midway position on the fastener 4 by the half-eye 3. The fastening eye of the button is engaged by passing it over either of the raised ends 7 of the fastener 4 and the button is disengaged by passing it out over either of the said raised ends 7. The half-eye 3 of the fastener 4 is directly across the center space within the coils from the raised wire ends 7 and in either lap strand of the coils. The wire ends 7 are rounded and raised for a distance of three

mm. at an angle of twenty-five degrees (25°) from the center strand perpendicular to a plane passing horizontally through the center of the coil 4. The half-eye 3 of the button-fastener has an opening sufficient to accommodate the diameter of the wire in the usual button fastening 2. The button-fastener 4 is circular in form. The half-eye 3 is raised perpendicularly to the plane passing through the center of the button-fastener 4 resting flat.

It will be noted that the raised ends of the wire in the button-fastener 4 admit the immediate engagement of the usual button fastenings 2 from either direction onto the button-fastener without any preliminary effort. Whenever the eye of the button fastening 2 is in contact with the said raised points or either of them it is engaged onto the aforementioned button-fastener. The said raised ends of the aforementioned button-fastener serve at the same time as adequate finger holds for engaging and disengaging the button 1. Once the button is on the button-fastener, it is allowed to articulate freely by the half-eye 3 but is at the same time held firmly in the position midway from the wire ends 7 at the opposite side of the button-fastener 4. The wire ends 7 being bluntly rounded and raised not more than three mm. in extent at an angle of 25° , prevents them from catching in the material in connection with which they may be used and damaging the same to any appreciable extent. While the button-fastener 4 being but a two lap coil, the button 1 is quickly put on and taken off it. The half-eye 3 does not permit the button to go farther than one-half way on the first lap of the coil button-fastener 4 and the button is thus permitted to be removed within one quarter of the time consumed by this operation with the ordinary button-fastener. Regardless of which of the two ends 7 you may select to start the button 1 onto the button-fastener 4 when it reaches the open space formed by the half-eye 3 it remains there but is free to move about until disengaged from the button-fastener.

I claim:

1. A button fastener comprising a strand of

resilient wire coiled to form a circular body having contacting convolutions, one convolution being crimped to form an eye projecting transversely from the body and having an open inner end bridged by another convolution whereby an attaching eye of an article may be threaded upon one end of the strand and moved along the same into the first mentioned eye and retained in engagement with said eye of the fastener by the second mentioned convolution thereof.

2. A button fastener comprising a strand of resilient wire coiled to form a circular body having contacting convolutions, one convolution being crimped to form an eye projecting transversely from the body and another convolution extending in bridging relation thereto to form a closure, the ends of said strand being bent to form prongs projecting diagonally from the body.

Signed in Manila, Philippine Islands, on February 28th, 1928.

ALFRED W. B. FREDERICK.
